UNITED STATES PATENT OFFICE.

FRIDOLIN POLZER, OF SOUTH NORWALK, CONNECTICUT, ASSIGNOR TO THE E. H. HOTCHKISS COMPANY, OF NORWALK, CONNECTICUT, A CORPORATION OF CONNECTICUT.

STAPLING MACHINE.

Application filed August 13, 1925. Serial No. 49,991.

This invention relates to stapling machines, and particularly to stapling machines of the type wherein a number of previously formed staples are held in a magazine and fed forwardly to a position from which they are driven by a suitable movable plunger, and has for an object to provide an improved feeding means for the staples which will be more reliable and efficient in operation and will feed the staples equally as well when the supply is nearly exhausted as when a large number of staples are in the machine.

It is also an object of the invention to provide a construction to facilitate and simplify the operation of inserting a new supply of staples in the machine.

It is a further object of the invention to provide improved holding means for the staple during the driving operation, and it is a still further object of the invention to provide a construction of this type of machine in which the operating mechanism may be assembled outside of the housing and inserted as a unit in this housing.

With the foregoing and other objects in view, I have devised the construction illustrated in the accompanying drawings forming a part of this specification, similar reference characters being employed throughout the various figures to indicate corresponding elements. In these drawings,

Fig. 1 is a partial side elevation and partial section through the housing at one side of the operating mechanism so that this mechanism is shown in elevation, the section being substantially on line 1—1 of Fig. 3.

Fig. 2 is a side elevation of the rear end of the machine showing how the staples are fed to the machine.

Fig. 3 is a front elevation of the machine with the face plate removed.

Fig. 4 is a section of the front end of the machine showing the position of the elements when the staple holding device is in its lowermost position but still functioning to retain the staple.

Fig. 5 is a similar view showing the plunger in its lowest position.

Fig. 6 is a detail section substantially on line 6—6 of Fig. 1.

Fig. 7 is a detail section substantially on line 7—7 of Fig. 8.

Fig. 8 is a section substantially on line

8—8 of Fig. 7 showing the spring mechanism in front elevation.

Fig. 9 is a transverse section substantially on line 9—9 of Fig. 1.

Fig. 10 is a view similar to Fig. 1 showing how the unit assembly is removed from and mounted in the housing.

Fig. 11 is a partial side elevation and partial section indicating how the feed mechanism is rendered ineffective while a new supply of staples is placed in the machine.

Fig. 12 is a vertical section through the spring mechanism for the feed.

Fig. 13 is a side elevation of the plate closing the open side of the barrel.

Fig. 14 is an end and side elevation of the arbor at the center of the barrel, and

Fig. 15 is a rear elevation of the machine looking from the right of Fig. 10.

The machine comprises the base 16 carrying the anvil 17 which cooperates with the plunger for setting the staples. This base has upwardly extending ears 18 between which the bar 21 is pivoted as at 20. A housing 19 carries the staple holding and guiding means comprising bar 21 inserted in the housing and somewhat narrower at its upper side than at its lower side as shown at 22 to allow space for passage of the prongs 23 of the staples between the side walls of the bar and the housing. The side walls of the housing are provided with inwardly extending ribs 24 a short distance above the top of the bar 21 to form guides to retain the staples on the bar, and they also provide a slot 25 in the top of the rear portion of the housing for passage of the handle 26 of the feeding element or follower 27. This element is substantially U-shaped in cross section as shown, and is inverted so as to straddle the top of the bar 21 and slide along the top of this bar. At its forward end it engages the staples mounted on the bar and tends to force them forwardly into position to be driven by the plunger through mechanism presently to be described.

At its forward part the housing is provided with an enlargement 28 forming a chamber for the feeding mechanism, this chamber being open at the front for insertion and removal of this mechanism. This feeding mechanism comprises a casing 29 which is open at its forward and lower sides

80

110

for insertion of the various elements. Mounted in this casing is a barrel or drum 30 mounted to rotate on a cross pin 31, and this barrel is substantially cup shaped so that it is open at one side which is closed by the disc 32. This disc is provided with a circular raised portion 33 which fits in the open side of the barrel as shown in Fig. 12 but it may rotate independently of the bar. 10 rel. This disc is also mounted to rotate on the cross pin 31 and is connected to an arbor 34 on this pin. A convenient means for connecting the arbor to the disc is to provide one end of the arbor with lugs 35 which 15 may extend into openings in the disc. A flat convolute spring 36 is mounted in the drum, one end thereof being connected to the arbor 34 and the opposite end being connected to the outer wall of the drum as shown in Fig. 20 7, so that this spring tends to rotate the drum counter-clockwise as viewed in Figs. 1, 7 and 11. Secured to the outer surface of this drum is a flat flexible strip of metal 37 which is wound about the drum and 25 passes at the lower side of the drum over a guide roller 38 located immediately above the top of the guide bar 21 and immediately to the rear of the plunger 39, and this strip then passes rearwardly over the top of the 30 bar and is connected to the feeding element or follower 27 by any suitable means, such as a screw 40. It will thus be apparent that as the spring 36 tends to rotate the drum counter-clockwise as indicated, it tends to 35 draw the feeding element 27 forwardly on the bar 21 and force the staples forwardly to a position under the plunger.

It is at times desirable to render this spring ineffective, especially when placing 40 a supply of staples in the machine and also during the assembling or disassembling of the machine. For this purpose a ratchet disc 41 is secured to the drum 30. It is mounted on the cross pin 31 and secured to rotate 45 with the drum by means of a stud 42 carried by the drum and projecting into an opening in this disc. This disc, has any desired number of teeth 43 in its outer periphery arranged to cooperate with a pawl 44 pivot- 50 ed in the casing 29 at 45. It will be apparent that this pawl when engaging a tooth of the ratchet will prevent the spring 36 from rotating the barrel to draw the feeding element 27 forwardly as described above. A spring 55 46 engages the lower arm 47 of the pawl 44 and tends to hold it in engagement with the ratchet. This lower arm is provided on its front side with a lug 48 the opposite sides of which are inclined as shown to form a 60 double cam, and this lug projects into the path of movement of a bar 49 on the plunger 39, so that as the plunger is reciprocated the pawl 44 will be lifted from the ratchet to 65 allow the spring 37 to function to advance the feeding element or follower 27.

The plunger 39 is preferably substantially rectangular in cross section and is guided for vertical reciprocation in the guideways 50 in the front of the housing. It is operated by the usual knob or head 51 secured to its upper end, which may be pressed downwardly by a blow of the hand or merely by forcing it downwardly. The plunger includes a plate 52 projecting below the lower end of the body of the plunger, which plate is substantially of the same thickness as the staples to be driven. When the plunger is in its uppermost position as shown in Fig. 1, the lower end of this plate is placed a short distance above the top of the bar 21 to allow the foremost staple on this bar to be forced by the follower 27 under this plate. 75

Means is provided to prevent the foremost staple dropping downwardly in the guideways 53 before the plunger is operated. 80 This comprises a spring strip 54 mounted in a guideway in the rear wall of the face plate 55. This face plate is secured in position at the forward side of the plunger to retain the plunger in the guideways 50, and it is secured to the housing by any suitable means as the screws 56. This plate is preferably made in two sections so that the lower section 57 immediately in front of the bar 21 may be removed if desired independently of the rest of the plate to remove any staples which might be clogged in the guideway at the front of the bar. The strip 54 is mounted to slide with the plunger throughout a certain portion of its movement and is turned inwardly at its lower end as shown at 58, toward the end of the bar 21 and under the forward staple to retain this staple under the lower edge of the plunger plate 52 as shown in Figs. 1 to 4. 85 As the plunger is forced downwardly the pressure of the plunger on the staple and the pressure of the staple on the inturned end of the spring will carry this plate 54 downwardly with the plunger so that it will retain the staple in position under the lower end of the plunger plate 52 until the plunger plate reaches the position, substantially shown in Fig. 4, with the prongs of the staple driven through the sheet of paper 59, when the movement of the plate 54 is arrested by the laterally bent upper end 60 engaging the top wall of the face plate 55. The lower end of this spring, however, is adapted in this position to move outwardly away from the end of the bar 21, and this is what it does do as the plunger continues its downward movement, and therefore, this further downward movement of the plunger forces the staple past the end of the spring and sets the staple. The staple is thus under the control of the strip or plate 54 until the upper end 60 thereof engages the top of the face plate 55 when the staple is forced downwardly by the further movement of the 100 105 110 115 120 125 130

plunger. If for any reason the plunger should be forced downwardly to the position shown in Fig. 4 and then be allowed to go back to its upper position without completing its downward movement it will move the spring plate 54 upwardly to its original position and carry the staple with it back to the position shown in Fig. 1. This is effected by the pin 61 engaging the upper end 10 of the slot 62 in the plate 54. It will be apparent that this slot and pin connection form a lost motion connection between the plate and the plunger to allow a further downward movement of the plunger from the position shown in Fig. 4 after the movement of the spring plate has been arrested. When in its upper position as shown in Fig. 1, the lower end of the spring plate 54 is held against the end of the bar 21 by the rear 20 wall of the face plate 55, and therefore, it cannot be pushed to one side by the force of the spring 36 of the staple feeding mechanism to cause the staples to be dropped from the machine when it is not in operation.

25 The disc 32 is provided with an arm 63 which projects into an opening 64 in the plunger 39 so that when the plunger is forced downwardly to drive a staple this arm will also be forced downwardly, rotating the disc 30 counter-clockwise as viewed in Figs. 1, 4 and 7, and will put an increased tension on the spring 36. This momentarily increased tension on the spring 36 tends to insure that a proper pull is applied to the follower 27 to 35 make sure that the staples will be fed forwardly as required. This spring also tends to lift the plunger to its upper position, but to insure that the plunger is brought back to this position after the pressure on the knob 51 is removed another spring 65 is connected to the arm 63 and its other end is connected to a pin 66 mounted in the upper part of the housing. The spring also tends to move the arm 63 upwardly and assists in 45 raising the plunger. The housing is provided with a recess 67 open at the front thereof into which this pin 66 may be inserted, the upper end of the spring passing through a slot 68 in the lower wall of this 50 recess. This additional spring is provided to secure a more reliable operation.

55 It is to be noted that the barrel 30 with the disc 32, the spring 36, and the ratchet and pawl 41-44 is mounted in the casing 29 so that it may be assembled as a unit outside of the machine and merely inserted as a unit through the opening in the front side of the enlargement 28 of the housing as indicated in Fig. 10, the lower edges of this 60 casing resting on the ribs 24 and the cross member 69. It may also be removed from the housing by merely removing the face plate 55 and the plunger and then drawing it forwardly through the opening in the 65 housing. The back wall of the enlargement

28 is provided with an opening 70 through which the follower 27 may pass in the assembling or disassembling operation. In disassembling, this follower is drawn backwardly out the rear of the machine by pulling on the handle 26 until it is free from the machine, as shown in Fig. 11, and it may be swung to one side free of the machine without danger of being drawn forwardly into the mechanism to break the strip 37 or injure the user, by means of the pawl and ratchet 41-44, which pawl and ratchet, as will be obvious, will render the spring 36 ineffective. The casing 29 may then be withdrawn from the housing and the follower 27 passed 80 through the opening 70 as shown in Fig. 10 to remove the entire mechanism from the housing. The assembling is merely a reversal of this operation.

85 The pawl and ratchet 41-44 also facilitates the feeding of a new supply of staples to the machine. By drawing backwardly on the handle 26 as described above the follower 27 may be withdrawn through the rear end of the machine and moved to one side, as indicated in Fig. 11, and the operator does not have to be careful to prevent its being drawn forwardly by the spring 36 either to injure the operator or break the strip 37, because the spring is held by the pawl and ratchet. The staples may be fed onto the rear end of the bar 21 from a holder 71 as shown in Fig. 2, this holder being placed to straddle the reduced rear end 72 of the bar and then the staples 73 are merely forced off this holder onto the bar 21. The follower 27 may then be returned to its normal position on the bar 21 and the pawl 44 released to allow the spring 36 to draw the follower forwardly to 100 bring the staples to the proper position. This pawl may be released by the operator by merely forcing the plunger 39 downwardly a short distance, which will cause the bar 49 on the plunger to engage the upper wall of the cam lug 48 and lift the pawl from the ratchet. This immediately releases the spring 46 allowing it to draw the feeding member forwardly. It is also to be noted that every complete reciprocation of the plunger during the operation of driving the staples will release the pawl 44 twice, once on its downward movement by engagement of the bar 49 with the upper wall of the lug 48, and then again on the upward movement of the plunger by engagement of the bar 49 with the lower wall of the cam lug 48. Therefore, the pawl is always released sufficiently on reciprocating movements of the plunger to allow the spring 36 to perform its necessary feeding operation for the staples to insure that there is always a staple under the plunger. The guide roller 38 insures that the pull of the strip 37 on the follower 27 is always par- 105 110 115 120 125 130

allel with the top of the bar 21, and it also insures that this follower can be drawn clear up to the forward end of the bar so that the last staple will be fed under the 5 plunger.

Having thus set forth the nature of my invention, what I claim is:

1. In a stapling machine, a staple guide having an upright wall, a plunger mounted 10 to move by said wall to drive and set the individual staples, a spring plate mounted at the opposite side of the plunger and movable throughout part of its movement with said plunger, said spring plate being provided with means coacting with the end of 15 the guide to hold the staple under the end of the plunger, and means to stop the movement of the spring before the plunger reaches the end of its movement to release 20 the staple.

2. In a stapling machine, a staple guide and support having an upright wall at one end, a plunger mounted to move by said end to drive and set the individual staples, a 25 spring plate mounted at the opposite side of the plunger and having an inturned lower end cooperating with said end wall to hold the staple under the plunger, said lower end being adapted to yield laterally away from 30 said wall, and the plate being movable with the plunger throughout part of its movement, and a stop to limit the movement of the plate at a given point in the movement 35 of the plunger to release the staple by further movement of the plunger.

3. In a stapling machine, means for driving and setting the individual staples, means for feeding the staples to the first mentioned means including a feeding element, a spring 40 and a flexible connection from the spring to said element to force the element forwardly, said feeding element being mounted so that it may be withdrawn rearwardly against 45 action of the spring to allow insertion of staples toward the driving means from the rear of the machine, and means to remove the tension of the spring from said flexible connection to render the spring ineffective 50 to advance the element during the insertion of the staples in the machine.

4. In a stapling machine, means for driving and setting the individual staples, means for feeding the staples to the first mentioned means including a feeding element, a spring 55 and a flexible connection between the spring and the element tending to force the element forwardly, means whereby the feeding element may be drawn rearwardly to allow insertion of the staples from the rear of the machine, and a catch to remove the tension 60 of the spring from said flexible connection to render the spring ineffective to advance said element during the insertion of the staples in the machine.

5. In a stapling machine, means for driv-

ing and setting the individual staples, means for feeding the staples to the first mentioned means including a feeding element and a spring tending to force the element forwardly, said element being mounted so that 70 it may be withdrawn rearwardly against action of the spring to allow insertion of staples, and means controlled by the staple driving and setting means for controlling the operation of the spring. 75

6. In a stapling machine, a movable plunger for driving and setting the individual staples, means for feeding the staples to operative position with the plunger including a movable feeding element and a 80 spring tending to move said element forwardly, said element being mounted so that it may be drawn rearwardly against action of the spring to permit insertion of staples, and means controlled by the plunger for 85 rendering the spring ineffective when the element is in the rearward position.

7. In a stapling machine, a movable plunger for driving and setting the individual staples, a support and guide for the staples, a follower movable along said guide to advance the staples, a spring, a connection from the spring to the follower, and means controlled by the plunger for 90 rendering the spring ineffective. 95

8. In a stapling machine, a movable plunger for driving and setting the individual staples, a support and guide for the staples, a follower movable along said guide to advance the staples, a spring, a rotary 100 drum connected to the spring, a flexible connection from the drum to said follower and adapted to be wound about the drum, and a pawl and ratchet to control the operation of the spring, said pawl and ratchet being 105 controlled by said plunger.

9. In a stapling machine, a movable plunger for driving and setting the individual staples, a support and guide for the staples, a follower movable along said guide 110 to advance the staples, a rotatable drum, a coiled spring in said drum and connected thereto, a flexible connection from the drum to the follower, a ratchet connected to the drum, a pivoted pawl arranged to cooperate 115 with the ratchet to hold the drum against rotation to advance the follower, and cooperating means on said plunger and pawl for releasing the pawl as the plunger is operated. 120

10. In a stapling machine, a movable plunger for driving and setting the individual staples, a support and guide for the staples, a follower movable along said guide to advance the staples, a rotatable drum, a coiled spring in the drum and connected at one end to the drum, a lever connected to the other end of the spring and also to the plunger for operation by said plunger, a flexible connection from the drum to said fol- 125 130

lower, and means controlled by the plunger for controlling the operation of said spring.

11. In a stapling machine, a movable plunger for driving and setting the individual staples, a support and guide for the staples, a movable follower for advancing the staples, a spring for advancing said follower, and means connecting the spring and plunger to increase the tension on the spring

10 as the plunger is operated to drive a staple.

12. In a stapling machine, a movable plunger for driving and setting the individual staples, a support and guide for the staples, a movable follower for advancing the staples, a spring for advancing said follower, means connecting the spring and plunger to increase the tension on the spring as the plunger is operated to drive a staple, and means controlled by the plunger for controlling the operation of the spring on the follower.

13. In a stapling machine, a movable plunger for driving and setting the individual staples, a support and guide for the staples, a movable follower for advancing the staples, a rotatable drum, a coiled spring in the drum connected at one end to the drum, a lever connected to the other end of the spring and arranged to be operated by the plunger to increase the tension on the spring as the plunger is operated to drive a staple, and a flexible connection from the drum to said follower.

14. In a stapling machine, a housing open at one side thereof, a support and guide for the staples, a movable follower for advancing the staples, a casing mounted in the housing and adapted to be inserted in and removed through said open side, means mounted in the casing for advancing the follower, a connection from said means to the follower, and means for driving and setting the individual staples.

15. In a stapling machine, a housing open at one side thereof, a support and guide for the staples, a movable follower for advancing the staples, a casing mounted in the housing and adapted to be inserted and removed through said open side, a rotatable drum mounted in the casing, a spring in the casing for rotating the drum, a flexible connection from the drum to the follower, and a movable plunger for driving and setting the individual staples.

16. In a stapling machine, a housing, a support and guide for the staples, a movable plunger for driving and setting the individual staples, and a unit assembly adapted for insertion in and removal from said housing as a whole, said unit assembly comprising a follower for advancing the staples, a spring for operating the follower, and means adapted to be controlled by the plunger for controlling the operation of the spring.

17. In a stapling machine, a housing, a support and guide for the staples, a movable plunger for driving and setting the individual staples, and a unit assembly adapted for insertion in and removal from said housing as a whole, said unit assembly comprising a rotatable drum, a spring tending to rotate the drum, and means operated by said drum for advancing the staples.

18. In a stapling machine, a housing, a support and guide for the staples, a movable plunger for driving and setting the individual staples, and a unit assembly adapted for insertion in and removal from said housing as a whole, said unit assembly comprising a follower for advancing the staples, a spring tending to advance said follower, and means adapted to be controlled by the plunger for controlling the operation of said spring.

19. In a stapling machine, a housing, a support and guide for the staples, a movable plunger for driving and setting the individual staples, and a unit assembly adapted for insertion in and removal from said housing as a whole, said unit assembly comprising a follower for advancing the staples, a rotary drum, a spring tending to rotate the drum, and a flexible connection from the drum to the follower.

20. In a stapling machine, a housing, a support and guide for the staples, a movable plunger for driving and setting the individual staples, and a unit assembly adapted for insertion in and removal from said housing as a whole, said unit assembly comprising a casing, a rotatable drum mounted in said casing, a coiled spring in the drum and connected thereto so as to tend to rotate the drum, a follower for advancing the staples, and a flexible connection from the drum to said follower.

21. In a stapling machine, a housing, a support and guide for the staples, a movable plunger for driving and setting the individual staples, and a unit assembly adapted for insertion in and removal from said housing as a whole, said unit assembly comprising a casing, a rotatable drum mounted in said casing, a coiled spring in the drum and connected thereto so as to tend to rotate the drum, a follower for advancing the staples, a flexible connection from the drum to the follower, a ratchet secured to the drum, and a pawl adapted to be controlled by the plunger arranged to cooperate with said ratchet to control the operation of the spring.

22. In a stapling machine, a housing, a support and guide for the staples, a movable plunger for driving and setting the individual staples, and a unit assembly adapted for insertion in and removal from said housing as a whole, said unit assembly comprising a casing, a rotatable drum mounted in said casing, a coiled spring in the drum and

connected at one end to the drum, a lever connected to the other end of the spring and operated by the plunger, a follower for advancing the staples, a connection from the drum to the follower, and means adapted to be controlled by the plunger for controlling the operation of the spring on the follower.

23. In a stapling machine, a housing open at the forward side thereof, a support and 10 guide for the individual staples, a casing adapted to be inserted in the housing through said open side, means mounted in the casing for advancing the staples, a reciprocating plunger, and means for securing and guiding 15 the plunger at the open side of said housing.

24. In a stapling machine, a housing open at the forward side thereof, a support and guide for the individual staples, a casing adapted to be inserted in the housing through 20 said open side, a follower for advancing the staples, means mounted in the casing for advancing the follower, said housing being provided with guide ways at the open side

thereof, a plunger for driving the staples mounted to reciprocate in said guideways, 25 and a removable plate for securing the plunger in said guideways and retain the casing in the housing.

25. In a stapling machine, a housing open at the forward side thereof, a support and 30 guide for the individual staples, a casing adapted to be inserted in the housing through said open side, a follower for advancing the staples, a rotatable drum in the casing, a connection from the drum to the follower, a 35 coiled spring in the drum and connected at one end thereto, a lever connected to the other end of the spring, a reciprocating plunger at the forward side of said housing for driving and setting the individual staples and 40 having operative connection with said lever, and a second spring secured to the lever tending to raise the plunger.

In testimony whereof I affix my signature.

FRIDOLIN POLZER.
